(57) **CLAIM**

The ornamental design for a monitoring camera with intercommunication device, as shown and described.

DESCRIPTION

FIG. 1 is a front, right, bottom perspective view of a monitoring camera with intercommunication device embodying our new design;
FIG. 2 is a front elevation view thereof;
FIG. 3 is a rear elevation view thereof;
FIG. 4 is a left elevation view thereof;
FIG. 5 is a right elevation view thereof;
FIG. 6 is a top plan view thereof; and,
FIG. 7 is a bottom plan view thereof.

The broken lines in the drawings are for the purpose of showing portions of the monitoring camera with intercommunication device that form no part of the claimed design.

1 Claim, 4 Drawing Sheets
